UNITED STATES PATENT OFFICE.

CIRIACO MARRA, OF MIDDLETOWN, CONNECTICUT.

DESIGN FOR A ROCKING CHAIR.

60,621.

Specification for Design.

Patented Mar. 14, 1922.

Application filed June 7, 1921. Serial No. 475,729. Term of patent 3½ years.

To all whom it may concern:

Be it known that I, CIRIACO MARRA, a subject of the King of Italy, (who has signified his intention of becoming a citizen of the United States,) residing in Middletown, in the county of Middlesex and State of Connecticut, have invented a new, original, and ornamental Design for a Rocking Chair, of which the following is a specification, reference being had to the accompanying drawing, forming part thereof.

The figure is a perspective of a rocking chair, showing my new design.

I claim:

The ornamental design for a rocking chair, as shown.

CIRIACO MARRA.
